UNITED STATES PATENT OFFICE.

WALTER HART, OF NEW YORK, N. Y.

DESIGN FOR A FLAGSTAFF-SOCKET.

SPECIFICATION forming part of Design No. 32,333, dated March 13, 1900.

Application filed February 8, 1900. Serial No. 4,564. Term of patent 14 years.

To all whom it may concern:

Be it known that I, WALTER HART, a citizen of the United States, residing at New York city, in the county of New York and State of 5 New York, have invented and produced a certain new and original Design for Flagstaff-Sockets, of which the following is a specification, reference being had to the accompanying drawing, forming part thereof.

10 The drawing shows a perspective view of my new design.

The chief features consist in the peculiar conformation of the socket, and particularly in the arrangement and conformation of the 15 American shield, showing thereon the stars and stripes.

In the drawing, A is the base from which the hollow portion B continues at a slight angle. This hollow portion B consists of the 20 shield C, which consists of a field gradually sloped away from a peak or point, as shown, and having the stars and stripes arranged upon it in substantially the manner shown, this arrangement being better understood 25 from the following description of its forma-

tion. A central longitudinal section of an American shield is cut out, leaving the two sides or wings of the same connected only by a narrow strip at the foot. The wings are then folded inward until their outward upper 30 points meet, thus bringing together at the center the upper parts of the outer edges, as shown at E. When the wings of the shield are folded together, as above described, the narrow strip which connects them assumes 35 the form of a loop, which constitutes the end portion D of the design and through which the end of the flagstaff is received into the socket, said end portion being at a sharp angle to the middle portion B. A cross-piece F, 40 not a part of the shield, is added to complete the design and strengthen the loop D.

What I claim is—

The design for a flagstaff-socket, substantially as shown and described.

WALTER HART.
